SATURATED DITHIENYL PROPYL AMINES AND PROCESS OF MAKING

Walter Mark Duffin, London, England, assignor
to Burroughs Wellcome & Co. (U. S. A.) Inc.,
Tuckahoe, N. Y., a corporation of New York

No Drawing. Application April 24, 1951,
Serial No. 222,741

Claims priority, application Great Britain
April 28, 1950

11 Claims. (Cl. 260—293.4)

1 The present invention relates to chemical compounds of pharmaceutical value and to processes for making the same.

3 - tertiaryamino - 1:1 - di - 2' - thiénylalk - 1 - enes of the type:

in which Th signifies a 2'-thienyl group, R¹ is hydrogen or an alkyl group containing from 1 to 3 carbon atoms and R² and R³ may be identical or different and be methyl or ethyl groups or NR²R³ may denote the morpholino-, pyrrolidino or piperidino-groups, are already known, various members of the series being described for example in co-pending U. S. application Serial No. 104,810, filed July 14, 1949, now U. S. Patent No. 2,561,899. They may be formed by dehydration of the corresponding carbinols, which themselves may be formed by a variety of synthetic routes.

Attempts to reduce the compounds of the type (I) by many usual hydrogenating processes either fail altogether or result in attack of the thiényl groups. We have now found that the double bond can be reduced by means of metallic sodium without at the same time attacking the thiényl groups whereby compounds of the general formula

where Th, R¹, R² and R³ or NR²R³ have the same meanings given above, are produced. Such compounds are novel and some are found to have a valuable analgesic and some a spasmolytic activity. Analgesic activity is most prominent in those compounds wherein R¹=CH₃. The compounds are conveniently administered in the form of their salts such as their hydrochlorides.

The identity of the acid used for preparing the salt is of no consequence for the physiological activity, however, providing it is not itself highly toxic. Choice of the acid to be used is governed by availability or convenience and all salts of the compounds of this invention with non-toxic acids are considered equivalent. For purposes of this application, the base and non-toxic salts thereof are to be regarded as equivalents.

The compounds of the present invention have the advantage in presentation, compared with analogous known dithienyl alkenylamines, that they are more stable to heat and to exposure to air which facilitates their sterilization.

The present invention therefore comprises a process for the production of compounds of the general formula (II) as above defined, by subjecting compounds of the type (I) as above de-

2 fined to reduction under such conditions that the thiényl groups are not attacked while the double bond is reduced, for example by means of metallic sodium in an alcohol (preferably an alcohol having not more than 6 carbon atoms) with or without the addition of water or in liquid ammonia, or by sodium amalgam and acid.

While these variations are equivalent in that they all suffice to produce the desired reduction, they are not all equally convenient or efficient. The reductions in ethanol frequently are incomplete and yields are in all cases less than quantitative, usually in the range of 50-70%. When complete reduction is secured the loss (from the quantitative yield) is due to de-amination which proceeds concurrently. Such cleavages are relatively prominent when amyl alcohol is used as the solvent for which reason, and also because it is harder to get rid of amyl alcohol at the end of the reduction, it is preferred to use propanol (either n- or iso), or 80% ethanol.

Completeness of reduction can be determined by the absorption spectrum of the product. The parent allylamines possess intense absorption ($\lambda=14,100$) at 290 m μ whereas the saturated amines have only feeble absorption ($\lambda=800$) at that wave length.

Alternatively, if a sample containing some of the unsaturated amine is heated to boiling in concentrated hydrochloric acid an orange color develops, which, on standing 15-30 minutes becomes an intense blue. This test, which is very sensitive has proved of great utility in determining the conditions for securing complete reduction in these reductions.

35 The invention also provides new pharmaceutically active compounds, having analgesic and spasmolytic properties, of the general formula (II) above defined. Particularly the invention comprises the compounds herein described or salts thereof.

The invention is illustrated by the following examples:

Example 1

45 Sodium metal (7 g.) was added gradually to a boiling solution of 3-dimethylamino-1:1-di-2'-thienylbut-1-ene (5 g.) in ethanol (70 ml.). When all had dissolved, the alcohol was evaporated, and the residue dissolved in water and extracted with ether, yielding 3-dimethylamino-1:1-di-2'-thienylbutane (3 g.), the hydrochloride of which had a melting point 161°-162° C.

Example 2

50 A boiling solution of 3-pyrrolidino-1:1-di-2'

thienybut-1-ene (5 g.) in ethanol (70 ml.) was added to sodium metal (7 g.) and worked up as above, yielding 3-pyrrolidino-1:1-di-2'-thienylbutane (3 g.); the hydrochloride of which melted at 154° C.

Example 3

Sodium metal (7 g.) was added to a boiling solution of 3-dimethylamino-1:1-di-2'-thienylbut-1-ene (5 g.) in amyl alcohol (100 ml.) and worked up as above, yielding 3-dimethylamino-1:1-di-2'-thienylbutane (2.7 g.).

Example 4

To a solution of 3-dimethylamino-1:1-di-2'-thienylbut-1-ene (5 g.) in 2 N-hydrochloric acid was added 3% sodium amalgam (250 g.). When the reaction was complete, the aqueous layer was decanted, treated with excess ammonia solution of specific gravity 0.880 and extracted with ether, to yield 3-dimethylamino-1:1-di-2'-thienylbutane (1.5 g.).

Example 5

A slight excess of sodium metal was added to 3-dimethylamino-1:1-di-2'-thienylbut-1-ene (5 g.) in a mixture of equal parts of ether and liquid ammonia. After the addition of excess ammonium chloride, the ammonia was allowed to evaporate and from the ether was obtained 3-dimethylamino-1:1-di-2'-thienylbutane (1.4 g.).

Example 6

Seven g. of sodium metal was added to a boiling solution of 5 g. of 3-dimethylamino-1,1-di-2'-thienylbutane in 100 cc. of n-propanol. When all the sodium had dissolved, the propanol was evaporated and the residue was dissolved in water and extracted with ether yielding 3.5 g. of 3-dimethylamino-1,1-di-2'-thienylbutane, identical with that obtained in Example 1.

Example 7

Sodium metal (40 g.) was added gradually to a solution of 3-dimethylamino-1:1-di-2'-thienylbut-1-ene hydrochloride (10 g.) in aqueous ethanol (400 ml., 80%) under reflux, and worked up as above, yielding 3-dimethylamino-1:1-di-2'-thienylbutane (7 g.).

Similarly, 3-diethylamino-1:1-di-2'-thienylbut-1-ene gave 3-diethylamino-1:1-di-2'-thienylbutane (hydrochloride melting at 123°-125° C.).

3-piperidino-1:1-di-2'-thienylbut-1-ene gave 3-piperidino-1:1-di-2'-thienylbutane (oxalate, melting at 111°-112° C.).

3-morpholino-1:1-di-2'-thienylbut-1-ene gave 3-morpholino-1:1-di-2'-thienylbutane (hydrochloride, melting at 185°-186° C.).

3-dimethylamino-1:1-di-2'-thienylprop-1-ene gave 3-dimethylamino-1:1-di-2'-thienylpropane (oxalate, melting at 182°-183° C.).

3-dimethylamino-1:1-di-2'-thienylhex-1-ene gave 3-dimethylamino-1:1-di-2'-thienylhexane (hydrochloride, melting at 136° C.).

3-ethylmethylamino-1:1-di-2'-thienylbut-1-ene gave 3-ethylmethylamino-1:1-di-2'-thienylbutane (hydrochloride melting at 124°-125° C.).

I claim:

1. Compounds of the class consisting of those having the formula

where $\text{N}=\text{B}$ is a member of the group consisting of dimethylamino, diethylamino, methylethyl-

amino, piperidino and pyrrolidino, and their non-toxic acid addition salts.

2. As a new compound 3-diethylamino-1:1-di-2'-thienylbutane.

3. As a new compound 3-pyrrolidino-1:1-di-2'-thienylbutane.

4. As a new compound 3-piperidino-1:1-di-2'-thienylbutane.

5. As a new compound 3-dimethylamino-1:1-di-2'-thienylbutane.

6. As a new compound 3-methylethylamino-1:1-di-2'-thienylbutane.

7. The process of producing bases of the formula

where R is a member selected from the group consisting of lower alkyl groups and hydrogen, $\text{N}=\text{B}$ is a member of the group lower dialkylamino, piperidino, pyrrolidino and morpholino, which consists of reducing the corresponding unsaturated amine

while dissolved in solvent and metal reducing combinations selected from the class consisting of (a) sodium metal and a lower alcohol (b) sodium metal and liquid ammonia and (c) sodium amalgam and a dilute aqueous mineral acid.

8. The process of producing bases of the formula

where R is a member selected from the group consisting of lower alkyl groups and hydrogen, $\text{N}=\text{B}$ is a member of the group lower dialkylamino, piperidino, pyrrolidino and morpholino, which consists of reducing the corresponding unsaturated amine

with metallic sodium while dissolved in n-propanol.

9. The process of producing bases of the formula

where R is a member selected from the group consisting of lower alkyl groups and hydrogen, $\text{N}=\text{B}$ is a member of the group lower dialkylamino, piperidino, pyrrolidino and morpholino, which consists of reducing the corresponding unsaturated amine

with metallic sodium while dissolved in isopropanol.

10. The process of producing bases of the formula

where R is a member selected from the group consisting of lower alkyl groups and hydrogen, N=B is a member of the group lower dialkylamino, piperidino, pyrrolidino and morpholino, which consists of reducing the corresponding unsaturated amine

with metallic sodium while dissolved in n-butanol.

11. The process of producing bases of the formula

where R is a member selected from the group consisting of lower alkyl groups and hydrogen, N=B is a member of the group lower dialkylamino, piperidino, pyrrolidino and morpholino, which consists of reducing the corresponding unsaturated amine

with metallic sodium while dissolved in 80% aqueous ethanol.
